SHEET 2 OF 2

CHARGING TRUCK FOR COKING FURNACE

SUMMARY OF THE INVENTION

This invention relates in general to accessory devices for coking furnaces and in particular to a new and useful charging truck including a body carrying a plurality of bunkers having lowermost ends with extensible portions which are interconnected by flexible pipe connections.

Charging trucks for charging coking coal into the coking chambers of coke furnaces are known which include bunkers having outlets of a smaller diameter than the outer casing of the furnace chambers into which they are to be positioned for charging purposes. The outlets of the bunkers are surrounded by telescopic jacket pipes which are lowered into the outer case frame and which prevent the escape of charging gases from the cases of the coking furnaces. All the jacket pipes of the charging truck are connected with a collecting tank or collecting pipe for the charging gases and the collected charging gases are burnt or washed before they are released to the atmosphere. The wash waters are treated and then used again. During the charging operation the various outer cases of the furnace are in communication with each other not only from the interior of the furnace chamber but also from the exterior of the chamber through the jacket pipes.

When this complicated exhaust system with jacket pipes arranged around the outlets is not provided, but instead the charging gases are exhausted into the riser and the receiver of the coking system, there is no second connection of the outer cases with each other outside of the chamber. The outlet sockets of the charging bunkers have the same inside diameter as the outer cases and during the charging operation they attach onto the outer case frames. Such a construction has a disadvantage that the coke fills into the inside chamber in the form of a pouring cone which extends to a considerable height so that these cones block the communication of the gas collector space of the furnace chamber from one charging case to another, so that it becomes separated into several compartments. This can happen when fine coal enters the furnace chamber and forms a dense curtain or veil which is not sufficiently permeable to gas to affect a pressure equalization. In the most unfavorable situation the zone of the gas collector space of an outer case is separated from that of the two adjacent outer cases. A regular escape and withdrawal of the charging gases can then no longer take place and despite the arrangement of the sealing devices between the outer case frame and the bunker outlet charging gases will escape from the sealing point because the overpressure in the chamber is so high that the seal is no longer effective.

In accordance with the present invention there is provided a charging truck having a plurality of bunkers with lower outlet portions which are interconnected by flexible connecting lines adjacent the outer ends at the location of the connection of the ends to the cases of the coking furnace. The flexibility of these connecting lines permits the individual lifting of each bunker or a lower extensible portion thereof either collectively or successively.

The collecting means of the bunkers can be equipped at the ends facing the riser with a slide valve and an easily detachable flexible connection with which it may be connected to a socket of the riser. There would then be a double connection during the charging operation to the riser once through the furnace chamber and also through the collecting pipe.

The connecting pipes are preferably designed so that any coal which has entered into them will drop automatically back into the bunker outlet. The sockets of the connecting pipes at the bunker outlet extend obliquely upwardly and they are joined by pipe bends or acute angled pipe sections, for example, by welding. The two outer bunker outlets each have a connection to the adjoining outlets. The inner ones have two, one to each adjoining outlet. When a collecting pipe is provided, only one connection socket for each bunker outlet is provided.

Accordingly, it is an object of the invention to provide a charging truck construction having a body supporting a plurality of bunkers, the bunkers having lowermost discharge ends which are connected together by flexible pipe connections.

A further object of the invention is to provide a charging truck construction for coking furnaces which is simple in design, rugged in construction and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWING

In the Drawings:

FIG. 1 is a partial schematic vertical sectional and partial elevational view of the roof of a horizontal coke furnace battery having a charging truck thereon and with the bin outlets interconnected by flexible pipes as constructed in accordance with the invention, and

FIG. 2 is a view similar to FIG. 1 of another embodiment of the invention wherein the bins are interconnected with the uptake through a collecting main.

DETAILED DESCRIPTION OF THE PREFERRED EMBODIMENT

Referring to the drawings in particular, the invention embodied therein comprises a coking furnace having a chamber roof 1 with a plurality of outer cases 2. A riser opening 3 is also defined in the roof 1 and it connects into a riser 4 having a bend 5 which leads into a large receiver 6. The ends of the roof 1 include supporting beams or stands 7, one of which carries a bracket 8 which supports the receiver 6.

In accordance with the invention the roof 1 is provided with a rail structure or trackway 9 for supporting the wheels 10 of a charging truck generally designated 50.

The charging truck 50 includes spaced beam portions 11 which carry the wheels 10 and which depend from a body portion 12. The body portion supports a plurality of coal bunkers or charging chutes 13 which are arranged in spaced relationship on the body at a spacing corresponding to the spacing of the outer cases 2. The bunkers are charged with coal through charging openings 14 at the top thereof. Each bunker includes an outlet cone or an extensible portion 24, the outermost ones being designated 24a. A rotary slide valve 18 is associated with each extensible portion 24 for opening and closing the discharge at the lower end of the extensible portion 24. The valve 18 is operated through an elongated link 16 which is connected to a handle portion 17 and moved by a rotatable control member 15.

Each extensible portion 24 includes a cone 23 which may be oriented into a cone receiver 25 of each outer case 2 of the furnace. After the truck is positioned to overlie the cases 2 the extensible portions 24, 24a are lowered into the associated case by means of a lowering mechanism which includes a link 22 connected to a crossmember 52 which supports each lower extensible portion 24. The crossmember 52 is guided by means of guide sleeves 54 and it may be raised or lowered by actuating a link member 21 which is pivoted on a support 19 and which is moved by the control of a fluid pressure cylinder 20.

In accordance with a feature of the invention each bunker outlet at the lower end of the extensible portions 24 and 24a carries a pipe socket 26, the innermost ones 24 carrying a socket 26 on each side and the outermost ones carrying a socket only on the inboard side. The sockets of adjoining

75 bunker outlets are connected with each other by flexible pipe

members 27. This interconnection of all of the outlets of adjacent bunkers insures the equalization of the pressure between the sections of the gas collector space of the furnace chamber during the charging operation so that this connection will not be interrupted, for example, by piled up coal cones accumulating within the furnace chamber. The pipe connections 27 are long enough to permit relative movement of the extensible portions of adjacent bunkers without interference.

In contrast to FIG. 1, all bin outlets 24, 24a in FIG. 2 have only one socket 26 which is connected with the flexible pipe 27a, which in turn opens into the collecting main 55. In order to increase the mobility, a telescopic pipe connection 56, comparable to a stuffing box, is arranged in the pipe 27a. The horizontal collecting main 55 passes over the entire hopper car and it carries at its end facing the uptake the connecting piece 61 which can be displaced by the lever system 57, 58 and 59 along with the stuffing box 60 which is connected with the socket 62 of the uptake 4. In this way the bin outlets are always connected with each other and with the uptake, so that pressure differences can be equalized at any time.

What is claimed is:

1. A charging truck for supplying coal to a plurality of cases of a coke furnace, comprising a body portion adapted to be positioned over the cases of the coke furnace, a plurality of bunkers on said body portion each having a lower portion with an outlet alignable with a respective case for the discharge of coal into the furnace therethrough, sealing means associated with each bunker outlet to seal the associated outlet against flow therethrough, and flexible conduit means interconnecting the outlets of all of said bunkers for equalizing the pressure therebetween.

2. A charging truck, according to claim 1, wherein said flexible conduit means comprises a socket on the outlet of each of said bunkers and a pipeline interconnecting said sockets of all said bunkers.

3. A charging truck for supplying coal to a plurality of cases of a coke furnace, comprising a body portion adapted to be positioned over the cases of the coke furnace, a plurality of bunkers on said body portion each having a lower portion with an outlet aligned with a respective case for the discharge of coal into the furnace therethrough, sealing means associated with each bunker outlet to seal the associated outlet against flow therethrough, a collecting main, and pipeline means connected between said collecting main and each of said bunker outlets.

4. A charging truck, according to claim 1, wherein said flexible conduit means includes a socket on each of said bunker outlets, said socket having a detachable connection, and flexible pipes interconnecting said detachable connection of all said bunkers.

5. A charging truck, according to claim 1, wherein said bunkers include an upper portion, the lower portion being movable and extensible relative to said upper portion, and means mounting said lower portion for extension and retraction in respect to said upper portion.

6. A charging truck, according to claim 5, wherein said sealing means includes a rotary slide valve carried by said lower extensible portion for opening and closing the outlet thereof, said flexible conduit means being connected to each lower portion below the associated slide valve.

7. A charging truck, according to claim 6, wherein said body portion has a plurality of spaced supporting beams, wheels carried by said supporting beams being adapted to ride over a trackway, and a trackway located above the roof of a coking furnace for supporting and guiding said wheels.

8. A charging truck, according to claim 3, including an outlet riser associated with said coke furnace, said collecting main being connected to said outlet riser.
